Nicholas G. Wedder, of Troy, N.Y.,
ass't to

St. Paul Shirk and Whitehead, of Chicago, Ill.

Letters Patent No. 2198 Dated Oct. 10-1865.

Design for a Cooking Stove.

The schedule referred to in these Letters Patent are making part of the same:

To all whom it may concern:

Be it known that I, Nicholas G. Wedder, of the City of Troy, in the County of Rensselaer, and State of New York, have invented or produced a new and original design for a Cooking Stove; of which the following is a full, clear and exact description, reference being had to the accompanying photographs, in which:

Fig. 1 is a perspective view of a cooking stove having my said new design; and

Fig. 2 is a front view of one of the doors or panels of the same stove, like parts being marked by the same letters in both figures.

My said new design for a cooking stove consists in the arrangement of a rose or clearly shown in fig. 1, on each of the three side doors or panels B, C and D, on each of two inclined sliding front doors E, F of a cooking stove, having an inclined projecting foot F, in front, and otherwise shaped and ornamented, so as to present an appearance like that represented by the aforesaid photographs.

What I claim as my invention or production and desire to secure by Letters Patent:

The above described design for a cooking stove.
